UNITED STATES PATENT OFFICE.

SAMUEL ORSON BROWN, OF REXVILLE, NEW YORK.

CURTAIN-RING.

SPECIFICATION forming part of Letters Patent No. 685,295, dated October 24, 1893

Application filed May 19, 1893. Serial No. 681,147. (No model.)

To all whom it may concern:

Be it known that I, SAMUEL ORSON BROWN, a citizen of the United States, residing at Rexville, in the County of Steuben and State of New York, have invented a new and useful 5 Curtain-Ring, of which the following is a specification.

My invention relates to curtain-rings, and more especially to that class of rings which 10 are constructed to form holders for the curtain.

The object of my invention is to produce a cheap and simple ring, made of a single piece 15 of metal, which will be adapted to hang slidably upon the curtain-pole and at the same time serve as a clasp to hold the upper edge of the curtain, thus dispensing with the necessity of using means separate from the ring to secure the curtain thereto.

With this object in view my invention consists in a curtain-ring composed of a single piece of metal bent to ring form, curved in cross-section for something over one-half the circumference of the ring, and having the two 20 ends bent outward and formed into V-shaped corrugations adapted to fit each other and hold the upper end of the curtain, the extreme outer ends of the strip being curved to form finger-holds for separating the curved corrugations from each other.

My invention further consists in the improved construction, arrangement, and combination of parts hereinafter fully described and afterward specifically pointed out in the 25 appended claim.

In order to enable others skilled in the art to which my invention most nearly appertains to make and use the same, I will now proceed to describe its construction and operation, reference being had to the accompanying drawings, forming part of this specification, in which—

Figure 1 is a perspective view of a portion of a curtain-rod and curtain connected together by rings constructed in accordance with my invention. Fig. 2 is a perspective view of a curtain-ring constructed in accordance with my invention detached from the pole and curtain. Fig. 3 is a side elevation 40 thereof. Fig. 4 is a vertical section taken centrally through the same. Fig. 5 is an edge view.

Like letters of reference mark the same parts wherever they occur in the different figures of the drawings.

Referring to the drawings by letters, A indicates a portion of a curtain-pole and upon which I have shown in Fig. 1 two rings B constructed in accordance with my invention. Each of these rings is composed of a single 55 piece of sheet metal, the cross-section of which, at the point where the upper side of the ring bears upon the pole, is curved, with the concaved side outward and the convex side in contact with the top of the pole to facilitate 60 the moving of the ring lengthwise thereon. This concavity decreases in depth until about the point B', where it disappears, the balance of the strip being flat. At the point B'', where the circle of the ring is completed, one end 65 of the strip is formed into V-shaped corrugations C and the other end into V-shaped corrugations D, which fit into each other. The extreme ends of the strips, beyond the corrugations, are formed into finger-holds C' and 70 D'. The ring being composed of elastic sheet metal, it is so formed that the tendency of its elasticity is to close the two sides of the corrugations C and D into each other, so that 75 any textile or other soft material placed between them will be securely clamped and held thereby.

In the practical operation of my invention the thumb and finger of the operator's hand are placed in the finger-holds C' and D', respectively, and forced apart, carrying corrugations C and D apart sufficiently to permit the ring to be passed over the top of the curtain-rod after the rod is already secured in position. Having placed a sufficient number 85 of rings upon the rod, each ring can be opened by the means before described, the upper edge of a curtain E inserted between the corrugations, and the pressure on the finger-holds released, permitting the elasticity of the ring 90 to press the corrugations of the ring together on the curtain and firmly hold it in position.

The simplicity, cheapness, and effectiveness of my invention will be apparent from the foregoing description, and while I have illustrated and described what I now consider 95 efficient means for carrying out my invention I do not wish to be understood as limiting myself to the exact details of construction shown 100

and described, but hold that such slight changes or variations as might suggest themselves to the ordinary mechanic would properly fall within the limit and scope of my invention.

Having thus fully described my invention, what I claim as new, and desire to secure by Letters Patent of the United States, is—

A curtain-ring composed of a single piece 10 of metal bent to ring form, curved in cross-section for about one-half the circumference

thereof, and open at the bottom, of the two strips bent outward and formed into V-shaped corrugations adapted to register with each other, the extreme outer ends of said strips 15 being curved to form finger-holds substantially as described.

SAMUEL ORSON BROWN.
